WILLIAM EDWARD LYFORD, OF THOMPSONVILLE, CONNECTICUT, ASSIGNOR
TO THE HARTFORD CARPET CORPORATION, OF THOMPSONVILLE, CON-
NECTICUT, A CORPORATION OF CONNECTICUT.

TRAY FOR STEAMING YARN.

No. 858,086.

Specification of Letters Patent.

Patented June 25, 1907.

Application filed July 6, 1906. Serial No. 324,930.

To all whom it may concern:

Be it known that I, WILLIAM EDWARD LYFORD, a citizen of the United States, and a resident of Thompsonville, in the county of 5 Hartford and State of Connecticut, have invented a new and Improved Tray for Steaming Yarn, of which the following is a full, clear, and exact description.

The invention relates to the art of producing printed warp, such as is used by carpet manufacturers and others in the production of tapestry and other carpets, rugs and the like.

The object of the invention is to provide 15 a new and improved tray for supporting printed yarn during the process of steaming the same, with a view to fix the color, the tray being arranged to allow the steam to readily penetrate all portions of the yarn in 20 a comparatively short time, and to allow compact nesting of a plurality of trays for steaming a large amount of yarn in a comparatively small space.

The invention consists of novel features 25 and parts and combinations of the same, which will be more fully described herein-after and then pointed out in the claims.

A practical embodiment of the invention is represented in the accompanying drawings 30 forming a part of this specification, in which similar characters of reference indicate corresponding parts in all the views.

Figure 1 is a perspective view of the improvement showing the yarn in position; 35 Fig. 2 is a plan view of the improvement, part of the yarn carrier being broken out; Fig. 3 is a plan view of the yarn carrier; Fig. 4 is a side elevation of the same, and Fig. 5 is an enlarged end view of a plurality of 40 nested trays, parts being shown in section.

The improved tray consists essentially of a skeleton frame A and a yarn support B adapted to support the yarn C and removably held in the skeleton frame A. The 45 skeleton frame A has end pieces A' each provided with legs A² and seats A³ on the top corners, for the reception of the legs A² of another skeleton frame, to permit of nesting a plurality of trays, as plainly shown in Fig. 5. The end pieces A' are connected with each other by the sides A⁴ in the form of angle-irons and connected with each other

by cross bars A⁵, which in turn are connected with each other at or near their middle by a longitudinal bar A⁶. Thus by the arrangement described the desired rigidity is given to the skeleton frame A. The sides A⁴ are provided at or near their middle with upwardly extending lugs A⁷ for supporting the sides A⁴ of another skeleton frame set or 60 nested on the seats A³ of the frame in question.

The yarn support B consists of a plate B', and on the top of this plate B' are secured or formed transversely extending ribs B² spaced 65 suitable distances apart and preferably of U-shape, as plainly indicated in Figs. 3 and 4. The ends of the plate B are reinforced by longitudinally extending short ribs B³ to which the ends of the yarn C can be attached 7c in the usual manner, so as to keep the yarn C in a properly stretched condition lengthwise on top of the yarn support B, that is, having the yarn stretched over the upper edges of the U-shaped cross bars B², thus 75 spacing the yarn from the top surface of the plate B'. The yarn support B is adapted to be placed into the carrier frame A, so that the under side of the plate B' rests on the top of the cross bars A⁵ and the longitudinal bar A⁶, and the ribs B² are preferably projected beyond the side edges of the plate B' to rest on the horizontal members of the sides A⁴ made of angle-iron, thereby supporting the 80 yarn carrier B and its yarns in the skeleton 85 frame A and without danger of the yarn support shifting in either a longitudinal or a transverse direction while in position in the skeleton frame A.

By reference to the left hand end of Fig. 2 90 it will be noticed that the plate B' is spaced at its side edges from the inner edges of the horizontal members of the sides A⁴ to allow steam to pass through the said space to the 95 yarn held on the top of the cross bars B². Now, by the arrangement described, the yarn support B properly supports the yarn throughout its length and in such a manner that the steam has ready access to the yarn with a view to properly steam the same, and it will also be noticed that the yarn support B can be easily set into the skeleton frame A and removed therefrom whenever it is desired to do so.

By the arrangement described the yarn support B is supported in the skeleton frame A at points between the bottom and top thereof, so that steaming spaces are had for the convenient circulation of the steam when a plurality of trays are nested, as indicated in Fig. 5

The yarn tray shown and described is very simple and durable in construction, is not liable to easily get out of order and a thorough and uniform steaming of the yarn is had when the device is used.

The yarn support is of very thin sheet metal, as are also the bars A⁵, A⁶, and when said support rests upon the bars A⁵, A⁶, the projecting ends of the ribs B² are above the frame sides as shown in Fig. 5, but the weight of the yarn on the support would cause the cross-bars A⁵ A⁶ to sag sufficiently so that the ribs would rest on the side frames

Having thus described my invention, I claim as new and desire to secure by Letters Patent:

1. A yarn tray having a yarn support comprising a plate, spaced transverse ribs on the said plate and projecting beyond the sides of the said plate and means engaging the projecting ends of the ribs for supporting the plate.

2. A yarn tray having a yarn support comprising a plate, U-shaped ribs on the top of the plate and extending transversely thereof and means engaging the ribs for supporting the plate.

3. A yarn tray having a yarn support comprising a plate, U-shaped ribs on the top of the plate and extending transversely thereof, the ribs being spaced apart and projecting beyond the sides of the said plate

and means engaging the projecting ends of the ribs for supporting the plate.

4. A yarn tray having a yarn support, comprising a plate, spaced transverse ribs on the said plate, spaced longitudinal ribs on the ends of the said plate and means engaging the transverse ribs for supporting the plate.

5. A yarn tray, comprising a skeleton frame and a yarn support, the said skeleton frame having end pieces, sides connecting the end pieces with each other, and cross bars connecting the sides with each other at points between the end pieces, and the said yarn support comprising a sheet metal plate adapted to rest on the said cross bars and having transverse ribs on top, the ribs projecting beyond the sides of the plate and being adapted to rest on the said frame sides.

6. A yarn tray, comprising a skeleton frame and a yarn support, the said skeleton frame having end pieces, sides connecting the end pieces with each other, and cross bars connecting the sides with each other at points between the end pieces, and the said yarn support comprising a sheet metal plate adapted to rest on the said cross bars and having transverse ribs on top, the ribs projecting beyond the sides of the plate and being adapted to rest on the said frame sides, the side edges of the plate being spaced from the inner edges of the said frame sides.

In testimony whereof I have signed my name to this specification in the presence of two subscribing witnesses.

WILLIAM EDWARD LYFORD.
